GLASS-WORKING.

1,323,507.

Specification of Letters Patent.

Patented Dec. 2, 1919.

Application filed February 23, 1915. Serial No. 9,878.

To all whom it may concern.

Be it known that I, FRANK L. O. WADSWORTH, a citizen of the United States, residing at Pittsburgh, in the county of Allegheny and State of Pennsylvania, have invented a new and useful Improvement in Glass-Working, of which the following is a specification.

My invention relates in general to a method and means for automatically charging a series of mold receptacles with molten vitreous material which is delivered thereto in a stream that flows directly from a tank or other large source of supply; and it relates particularly to the severing of the stream and the temporary support and shaping of the severed end during the interval of mold movement. The primary objects of the improvements set forth in this specification are: first, the severing of the stream in such manner as to obtain a clean cut and symmetrically shaped end; second, the temporary support of this cut end on non-conducting surfaces so as to avoid any substantial chilling of the molten material; third, the shaping, if desired, of the severed end of the non-conducting support so as to avoid "lapping" of portions of the molten stream and so as to also bring it to such form as to more effectively charge the next receiving mold; and, fourth, the delivery, without distortion, of the freshly shaped end of the stream to the mold at any desired time in the cycle of the mold machine manipulations. Other objects of my improvements are the provision of improved mechanism for carrying out the various steps of the above described procedure in a simple and effective manner, and the construction of the parts of the mechanism in such manner as to least affect the temperature and the physical condition of the material being operated upon. Still other objects and advantages of my improvements will more clearly appear from the detailed description which follows.

In the accompanying drawings, which form a part of the disclosure of my improvements, Figure 1 represents in vertical cross section one form of mechanism adapted to practise my invention; Fig. 2 is a plan projection, on the plane X X of Fig. 1 of the upper portion of the said mechanism; Fig. 3 is a vertical sectional elevation to the left of the plane Y, Y of Fig. 1; Fig. 4 is a sectional plan view of the parts of the mech-

anism below the plane Z Z of Fig. 3; Figs. 5 and 6 are partial sectional views in the plane of Fig. 1 showing the parts in different operating positions; Fig. 7 is an elevation in partial section at right angles to the plane of Fig. 1.

In the construction illustrated in the above figures, 1 indicates a "flow block" chamber or "dog house" extending out from the front of a melting tank or other large receptacle for the preparation of the molten material 2. This flow block chamber is provided with an opening 3 preferably in the bottom, and below this opening is placed a metallic guard or flow ring 4 which serves to determine and control the size of the stream issuing from the opening. The volume of the flow per unit of time is regulated in part by the temperature maintained in the flow block chamber, in part by the vertically movable plug 5, and in part by the temperature of the ring 4 which can be varied within quite wide limits by varying the circulation of water or other fluid adjacent the flow ring plate 6. This latter plate is so constructed that the flow ring 6 can be readily removed and replaced by another of different size, when it is desired to vary the flow to a greater degree than is possible by joint regulation of the temperature of the chamber and the ring and by manipulation of the plug 5.

The mechanism which I use for severing the stream of material flowing from the orifice in the ring 4 is shown in vertical cross section in Fig. 1 and in plan view in Fig. 2. It comprises two shear blades 7 and 8, one of which is attached to the guide plate 9 that slides in ways on the top of frame 10, and the other of which slides on ways in the plate 9 itself (as best shown in Figs. 2 and 3). The left hand end of the plate 9 carries a cylinder 11; and the piston 12 of this cylinder is supported in a fixed position on an L-shaped projection from a bracket 13 which is carried by the frame 10 (as best shown in Figs. 4 and 7). The bracket 13 is bored to receive the fixed stud 14 on which is mounted a segmental pinion 15 that engages with rack teeth 16 on the guide plate 9. This pinion also carries a crank pin 17 which is connected by the link 18 with the shear blade 8. The piston 12 is provided with an air duct 19 that leads through the bracket extension 13 and the stud 14 and

communicates with a fluid supply pipe 20 having a three way valve 21 by means of which said pipe can be connected either with a source of compressed air or with an exhaust conduit 22.

Just below the plane of the shear blades 8 and 9—which are preferably arranged at a slight angle to the horizontal—I place two reciprocating support blocks 25 and 26, the first of which is attached to bars 27, 27 that slide in grooves in the side plates of main frame 10, and the second of which is attached to a plate 28 that carries a cylinder 29 and is provided with side lugs 30, 30 which fit between the lower edges of the bars 27, 27 and the upper edges of the guiding grooves for the said bars. The front ends of the bars 27, 27 are connected by a cross bar 31 which is coupled to the piston 32 in the cylinder 29 by the piston rod 33. A pinion 34 is mounted on a second stud 35 in the fixed bracket 13 and engages with two racks 36 and 37 that are secured respectively to one of the side bars 27 and to the cylinder 29. An air duct leads from the inner face of the piston 32 through the piston rod 33 and the cross head 31 to an elongated port 38 in one of the side bars 27. This port is in registry with the end of a pipe 39 which contains a three way valve 40 by means of which the said pipe can be put into communication either with a source of compressed air or with an exhaust conduit 22.

The valves 21 and 40 are operated by the joint action of a spring 41 and cams 42 and 43, that are mounted on a shaft 44 driven by the table moving mechanism at such speed that the said shaft and cams make one complete revolution in the interval between two successive mold movements. The receiving molds or receptacles—one of which is indicated at 45 in Fig. 1 and another of which is indicated by 46 in Fig. 45 6—are mounted on a suitable table and are brought in succession to the charging or filling position immediately below the orifice 3 by any suitable mechanism.

The operation of the above described mechanism is as follows:—A mold such as 45 is left in the charging position—as indicated in Fig. 1—until a sufficient quantity of molten material has accumulated therein. The valve 21 is then operated by the cam 42 to admit compressed air to the pipe 20 and the cylinder 11. This moves the frame 9 and its attached shear blade 7 to the left and simultaneously imparts—through the action of the rack 16, crank pinion 15 and link 18—a reverse differential movement to the shear blade 8. This movement continues until the two shear blades have been brought to the dotted line position of Fig. 5; in which position the stream has been severed and the cut end is supported sym-

metrically in the flat V-shaped pocket between the cutting edge of the blade 8 and the top face of the blade 7. Immediately after the closing of the shear blades 7 and 8, the valve 40 is opened by the cam 43 to admit compressed air to the pipe 39 and the cylinder 29. The pressure in this cylinder drives the piston 32, and the support block 25 coupled thereto, in one direction and cylinder frame 28, and the support block 26 carried thereby in the opposite direction; equality in these movements being secured by the engagement of the idle pinion 34 with the racks 36 and 37. This brings the blocks 25 and 26 together to the position shown in Fig. 5 and forms a central supporting pocket or cavity 47 whose axis coincides with the central line Y Y of the orifice 3 and closed shear blades 8, 9. Simultaneously with the closing of the support blocks, the valve 21 is closed by the joint action of the spring 41 and cam 42 so as to cut off the supply of compressed air from the cylinder 11 and place the latter in communication with the exhaust pipe 22. This withdraws the air from the cylinder 11 and the external pressure of the atmosphere returns the shear blade members to their open position as shown in Figs. 1, 2 and 5. This allows the freshly cut end of the severed stream—which has been only momentarily held on the closed shear blades, while the support blocks are being brought together as just described—to drop down with the pocket or cavity 47. The molten material is allowed to flow directly into the closed pocket until the latter is either wholly or partially filled as shown in the full and dotted lines of Fig. 5, the length of time of flow being governed principally by the form and character of the receiving molds 45, 46, etc. When the desired quantity of material has accumulated in the support pocket 47 the valve 40 is opened by the joint action of the spring 41 and cam 43, thus cutting off the supply of compressed air from the pipe 39 and cylinder 29 and placing the latter in communication with the exhaust 22. The external pressure of the atmosphere on the piston 32 then moves the parts quickly to open position as shown in Figs. 1 and 6 and permits the mass of molten glass that has accumulated in the support pocket 47 to drop in a body into the bottom of the receiving mold. If the quantity of glass thus delivered to the receiving receptacle is not sufficient, the molten stream is allowed to flow directly from the orifice 3 down through the opened shear blades 7 and 8 and opened support blocks 25 and 26—as shown in Fig. 1—until the required amount has accumulated in said receptacle and the shear blades are then closed to sever the stream and initiate another cycle of operations like that above described.

In some lines of manufacture there are a number of advantages in interposing a secondary support element between the cut off knives and the receiving molds and using this secondary element to not only support the severed end of the stream during the interval of mold movement, but also in certain cases to shape this end into special form for delivering to the receiving receptacle. Thus, for example, when the molten material must be flowed at a very high temperature, as is necessary with certain kinds of glass, the arrest of the flow by the action of surface tension or by the use of an air or gas blast; or the support of the severed stream on the cutting blades themselves; is impractical or highly undesirable, both because of the chilling of the molten glass and because of the intense heating of the metal shear blade surfaces. In the mode of operation above described, the glass rests on the shear blades 7 and 8 only for an exceedingly brief interval and it will not, therefore, be materially chilled, nor will the cutting knives be sensibly heated, no matter how high the temperature of the glass may be. The temporary support of the flowing molten material in the cup or cavity 47 will not sensibly affect its temperature for the reason that the walls of this cup are preferably made of some material which has a high heat resistancy; such as "mold paste", (the material used in forming the so-called paste molds employed in the production of many forms of blown articles) or compressed carbon or soapstone, or even manganese steel; and these support blocks may also be maintained at any desired temperature by the use of suitable electric heaters—such as are indicated at 48, 49, Figs. 1, 5 and 6—supplied with current by sliding contacts on the bars 27 and frame 28. By the use of such a material, there will be obtained a so-called "soaking" action in the glass, which will obliterate shear marks.

A further advantage of using separate and independent elements for first severing the stream and then supporting the cut end and the oncoming portions while the molds are being moved—or for an even longer interval, if desired—is that while the flowing material is thus being supported it may also be shaped in a globular or ovoid mass—or to any similar form desired—which is of such an outline as to be deposited to best advantage in the bottom of the receiving receptacle. This preliminary shaping of the molten charge to a definite predetermined form before its delivery to the mold in which it is to receive its final treatment, may be of great advantage in cases where the cavity of the said receiving mold is very deep or is of such cross-sectional outline as to make its filling direct from the flowing

stream of glass a difficult and unsatisfactory one.

Still another advantage of using an intermediate supporting element, which as just stated may also, if desired, be utilized as a preliminary shaping element, is that the glass may, during its time of delivery, be maintained in a hotter and more homogeneous condition in the heated non-conducting intermediate support than it can be in a receiving press mold which must necessarily be made of soft mold iron, maintained at relatively low temperature. By the use of the intermediate support, the glass may be "gathered" in a compact globular mass of the requisite quantity to "charge" the press mold in a single lump (in much the same way as such molds are charged by hand gathering) instead of filling it by the flowing stream in successive increments. This not only prevents a continuous chilling of the bottom portions of the glass by the iron surface of the mold, but also prevents the "lapping" or folding over of the stream of molten material as it accumulates in the mold and thus eliminates to a large extent the danger of entraining bubbles of gas or air, which form "blisters" in the finished article. The "lapping" of the material in the temporary support or gathering cup 47 is prevented in whole or in part by placing this cup very close to the cut off members and to the flow orifice and so shaping the interior of the cavity that the stream of glass is nearly as large in diameter as the cavity itself; the consequence of this being that the mass in the cup is gradually built up by the flattening and lateral swelling of the lower end of the flowing stream as shown by the successive lines of Fig. 5 without any folding over of the latter on itself. When the accumulated mass in the cavity 47 is dropped as a unit into the receiving mold, it flattens out on the bottom of that mold without any "lapping" of the material on itself.

It will be obvious that the exact form of the intermediate support cavity can be varied to best adapt the operation to the production of articles of different shape and size. It is also obvious that various forms of cut off mechanisms may be used for the severance of the glass stream at the required intervals. It is further apparent that the practice of my invention is in no way dependent upon the use of any particular mold-shifting mechanism and that the cut off and intermediate support devices above described—or their mechanical equivalents—may, if desired, be used to charge a series of receiving receptacles which are brought to and removed from the charging position by hand.

For these reasons I do not limit my claims to any specific form of cutting device, or

any particular form of intermediate support device, or any combination of these two devices with mold actuating mechanism. Nor do I desire to limit my claims 5 to the use of an intermediate support of any particular material, although I prefer to use a non-conducting or thermally insulating substance (using those terms to denote substance having a high heat 10 resistivity) for this element; and I prefer also to maintain that portion of the support which is in contact with the glass at the highest possible working temperature. I believe that the use of separate 15 and independently actuated elements or instrumentalities for severing a flowing stream and then supporting and shaping or "gathering" the severed end and the oncoming portions of the stream into any desired 20 form preliminary to its delivery to the final forming mold or receptacle, is broadly new and what I claim therefore is:

I claim as my invention:

1. In an apparatus of the character described, the combination of a pair of shear- 25 ing members between which a laterally-free stream of glass may flow, a pair of cup-forming members arranged below the shear members in position to receive the stream 30 without lapping and formed to approximate the lower portions of a mold, the said mold, and means for successively actuating the shear members and cup-forming members whereby both the shear members and the 35 cup-forming members may at times be laterally separated to permit direct flow of the glass stream and the shear members may be opened and closed to sever the stream and the cup members may be brought together 40 after the stream severance and held together subsequent to the opening of the shears.

2. In an apparatus of the class described, the combination of a pneumatic cylinder, 45 and coacting piston, means for holding one of said members stationary, a rack carried by one of said members, a pivoted segment carried by the other of said members and meshing with said rack, a pair of coacting 50 shear members, one of said shear members carried by the movable member of the cylinder and piston structure, and connections between the segment and the other shear blade.

55 3. In a machine of the class described, a cutting mechanism comprising a support, a segment pivoted on said support, a rack meshing with said segment, a cylinder and coacting piston, one carrying the rack and 60 the other the segment, a shear blade carried by the movable member of the cylinder and

piston structure, a coacting shear blade, and a connection between said last-mentioned shear blade and the segment.

4. In an apparatus of the character de- 65 scribed, a pair of mating members formed to coöperate with a stream of plastic material, supports for said members permitting movement thereof toward and from the axis of such stream, a pneumatic cylinder carried 70 by one of said members and a coacting piston carried by the other, and intermediate connections between said members to coördinate the movements thereof.

5. In an apparatus of the character de- 75 scribed, a pair of mating members formed to coöperate with a stream of plastic material, supports for said members permitting movement thereof toward and from the axis of such stream, a pneumatic cylinder 80 carried by one of said members and a coacting piston carried by the other, a pair of racks carried by said members, and a pinion connecting said racks.

6. In an apparatus of the class described, 85 a pair of mating members forming together a stream-receiving cup, and heating means for maintaining said members at a desired high temperature.

7. In an apparatus of the class described, 90 the combination with means for establishing and maintaining a flowing stream of glass, a mold arranged in the flow line of said stream, means arranged between the mold and the stream-establishing means for receiving said stream and preliminarily forming its lower end to correspond with low 95 portions of the mold without lapping, and cutting means arranged between said stream-receiving means and the stream orifice. 100

8. In an apparatus of the class described, the combination with means for establishing and maintaining a flowing stream of glass, a mold arranged in the flow line of said stream, means arranged between the 105 mold and the stream-establishing means for receiving said stream and preliminarily forming its lower end to correspond with low portions of the mold without lapping, cutting means arranged between said stream-receiving means and the stream orifice, and heating means for maintaining said preliminary forming means at a desired high 110 temperature.

In witness whereof, I have hereunto set 115 my hand at Pittsburgh, Pennsylvania, this 20th day of February, A. D. one thousand nine hundred and fifteen.
